UNITED STATES PATENT OFFICE.

ALBERT B. McMILLAN, OF AUBURN, WASHINGTON.

DESIGN FOR A STOVE.

SPECIFICATION forming part of Design No. 28,601, dated May 10, 1898.

Application filed January 29, 1898. Serial No. 668,494. Term of patent 3½ years.

To all whom it may concern:

Be it known that I, ALBERT B. McMILLAN, a citizen of the United States, residing at Auburn, in the county of King and State of Washington, have invented and produced a new and original Design for a Stove; and I do hereby declare the following to be a full, clear, and exact description of the same, reference being had to the accompanying drawing, forming a part thereof.

In the accompanying drawing the figure represents a perspective view of a stove embodying my design.

The leading feature of my design consists of an approximately rectangular - shaped stove-body, a circular opening in the side of said body for the reception of a cylindrical-shaped oven, a draft and fuel-supply opening in the front, and approximately rectangular-shaped doors covering said oven and supply opening, the doors resting in suitable ways formed on the outside of the stove.

A in the drawing represents the body portion of the stove, which appears rectangular in shape and is composed of side and end pieces having bent-over or folded end portions, as a. One of the sides of the stove A, as a', is provided with grooved or channel-like formations, as a², arranged horizontally. On

this side a' also appears a circular aperture 30 a³, arranged between the said channel-like formations a². This opening is closed by a door D, which is approximately rectangular in shape, said door being formed with a rolled handle-like portion d.

B represents a cylindrical-shaped oven which appears in the rear portion of the stove. On the front outer edge of the oven is an outwardly-flaring flanged formation d'.

C indicates a draft and fuel-supply door 40 provided on the front end of the stove and which is approximately rectangular in shape and on which appears a handle-like formation.

On the top of the stove appears a circular 45 aperture, as e, in which appears a stovepipe E of cylindrical shape.

Having now described my invention, what I claim as new, and desire to secure by Letters Patent, is—

The design for a stove, substantially as herein shown and described.

In testimony whereof I affix my signature in presence of two witnesses.

ALBERT B. McMILLAN.
